(57) **CLAIM**

The ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is an enlarged view of the portion 9 encircled in FIG.

5.

The evenly-spaced dashed broken lines in the figures that are immediately adjacent to the shaded areas and define unshaded regions, and the dot-dash broken lines, depict the bounds of the claim. The appearance of any portion of the article between the pairs of the dot-dash broken lines forms no part of the claimed design. All other evenly-spaced dashed broken lines, including the features within broken line boundaries and the broken lines on the front surface to the right and left of the speaker are directed to environment.

(Continued)

The dot-dot-dash broken lines in the drawings encircle portions of the claimed design that are illustrated in enlargements. All broken lines in the drawings form no part of the claimed design.
